RAIL FLANGE LUBRICATOR

Charles Stern, Jersey City, N. J., assignor to
Ardeco Manufacturing Company, Hoboken, N. J.,
a corporation of Delaware

Application September 29, 1933, Serial No. 691,550

24 Claims. (Cl. 184—3)

The present invention relates to lubricators, and more particularly to a lubricator of that type adapted to be mounted against a rail for supplying lubricant along one side of the head of the rail so that the lubricant may be picked up by wheel flanges and distributed for a considerable distance along the side of the rail from the lubricator.

An object of the present invention is to provide an improved and simplified construction of lubricator wherein the lubricant is fed directly from a distributing pipe through suitably spaced nozzles carried thereby into the desired spaced apart positions along the side of the rail head, and to provide a protecting plate or means for preventing damage to the nozzles by the flanges of wheels passing over the rail.

Another object of the present invention is to provide a construction wherein the parts are so mounted that the device may be adjusted and properly applied to rails worn to various degrees and to provide a lubricator comprising but relatively few parts which may be quickly interchanged upon wear or breakage of the parts, and wherein the lubricator as a whole will accomplish the purpose by a relatively short flat structure which lies close against the rail and occupies but small space.

Another feature of the present invention is to provide a lubricator with a distributing pipe so constructed and mounted that the pipe may serve as a bearing upon which the pipe may be rocked to dispose the nozzles of the pipe in the desired proximity to the rail head, and to provide means for facilitating the cleaning out of the pipe and nozzles.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side elevation of a rail flange lubricator embodying the features of the present invention and shown as applied to a portion of a rail.

Figure 2 is a like view but with the protector plate removed.

Figure 3 is an end elevation of the lubricator as applied to the rail.

Figure 4 is a transverse section through the same taken on the line 4—4 of Figure 1 and showing the passages through the distributing pipe and an adjacent nozzle.

Figure 5 is a transverse section taken through the lubricator applied to a rail on the line 5—5 of Figure 1 and showing the position of the protector plate over the feeding nozzles.

Figure 6 is a detail perspective view looking 5 at the inner side of the protector plate.

Figure 7 is a top plan view of the bracket employed for attachment to the rail web, and

Figure 8 is a fragmentary perspective view of one end of the bracket, showing the vertical slots 10 for adjustment and the supporting blocks for the protector plate and distributing pipe clamps.

Referring to the drawings a conventional type of rail is shown having a base 15, a web 16 and a head 17 at the top of the web which overhangs 15 the opposite sides of the base 15.

The lubricator has a bracket plate 18 which is of less height than the web 16 and which is of desired lengths and provided at suitable points, such as near its opposite ends, with vertically elongated slots 19 through which engage clamping bolts 20 or the like for binding the bracket 18 against the rail web. The bracket plate 18 is supported from the base 15 of the rail by means of set screws 21 which are threaded downwardly 25 through lugs 22 projecting from the opposite lower corners of the bracket 18 and which are adapted to be turned down for raising the plate when the clamping screws 20 are released. The bracket plate 18 is thus securely bound against the rail 30 web in adjusted position and is securely supported from sagging by the set screws 21.

The inner face of the bracket 18 is relatively flat, as shown in Figure 7, while the outer face thereof is provided at suitably spaced apart points 35 with supporting blocks 23 which stand out from the plate to the desired extent and which are provided with upwardly and inwardly inclined outer faces, the outer faces of all of the blocks 23 lying substantially in a common inclined plane. 40

Each block 23 is provided with an outwardly extending threaded stud 24 adapted to receive thereon a clamping nut 25 for a purpose which will hereinafter appear. At each end of the bracket 18, and at its outer side, is an outstanding flat rib 26 which preferably extends throughout the height of the bracket 18 and which is provided near its upper end with an outstanding threaded stud 27 upon which is secured one of the clamping nuts 25, the stud 27 being preferably 50 in line with the studs 24.

Mounted on the bracket is a distributing pipe 28. The pipe 28 is of suitable diameter and of a length slightly broader than the bracket 18 and bears at its opposite ends and at its inner side 55

against the lower portions of the ribs 26. The intermediate portion of the distributing pipe 28 lies beneath the blocks 23, and the pipe 28 is provided intermediate its ends with an attaching socket 29 or the like by means of which a source of lubricant under pressure may be connected.

The distributing pipe 28 is provided at opposite ends with removal plugs 30 by means of which the opposite ends of the pipe 28 may be opened for the purpose of cleansing the pipe, and also to facilitate manufacture of the device. The pipe 28 is held to the bracket 18 by a pair of clamps 31 which are provided with socketed or strap portions at their lower end conforming to the size and curvature of the pipe 28 and which at their upper ends are provided with flat lug portions adapted to seat against the upper portions of the ribs 26.

These lugs of the clamps 31 are apertured to engage over the adjacent studs 27 and have their outer faces inclined to lie in the plane of the outer faces of the blocks 23. The clamps 31 may be loosened sufficiently to turn the pipe 28 therein so as to turn the pipe to the desired degree for adjusting the distributor against the side of the rail. The clamps 31 not only hold the pipe 28 from turning when adjusted, but also rigidly support the distributing pipe on the bracket 18.

The distributing pipe is provided at its upper side with a desired number of distributing nozzles 32 which are in the form of small pipes secured to and communicating with the header pipe 28 and which extend upwardly therefrom and gradually merge into relatively flat broad outlet ends 33 which lie in a common plane lengthwise of the main pipe or header 28. These nozzles 32 consecutively increase in internal cross sectional area toward the opposite ends of the header or pipe 28 from the inlet flange 29 to equalize the feeding of the lubricant along the distributor throughout its length. The flattened upper ends of the nozzles 32 are adapted to lie against the side of the rail head 17, as clearly shown in Figures 3 and 4, so as to deposit at separate spaced points along the rail head desired amounts of lubricant so that such lubricant will be in the path of the flanges of wheels which pass over the rail to be carried by the flanges and deposited along the rail head beyond the lubricator.

A protector plate 34 is disposed over the upper ends of the nozzles 32 for protecting the same against damage, particularly by contact with the flanges of the wheels. This protector plate has a flat inner face, as shown in Figure 6, adapted to engage and rest upon the outer inclined faces of the blocks 23 and the lugs on the upper ends of the clamps 31. From Figure 2 it will be noted that the nozzles 32 lie between the blocks 23 so that the nozzles are housed and protected not only between the blocks 23 but between the bracket plate 18 and the outer protecting plate 34. The nozzles therefore cannot be crushed by impact of objects brought against the side of the rail. The protector plate 34 is inclined upwardly and inwardly toward the head 17 of the rail and is adapted to lie at its upper edge flat thereagainst. The protector plate is beveled at its outer side as at 35 and along its upper edge so as to lie closely against the side of the rail head 17 and take up the thrust and wear of the wheel flanges, and the protector plate 34 is provided near its lower edge with vertically elongated slots 36 through which engage the thread-

ed studs 24 and 27, the binding nuts 25 bearing against the outer side of the protector plate 34 for securing the same in vertically adjusted position.

The protector plate may be made of steel or any other hard material and its upper edge is preferably reinforced with some hardened substance, such as an alloy steel, to increase the wear resistance quality of the protector plate.

The lower edge portion 37 of the protector plate 34 is relatively thick and uninterrupted throughout the length of the protector plate so as to give the necessary strength and rigidity thereto, and the protector plate is provided at suitable spaced apart points and in its inner side with 15 recesses or depressions 38 which extend from a point in spaced relation to the lower edge of the protecting plate though the upper beveled edge thereof. These recesses 38 are disposed at points between the blocks 23 to receive and house the 20 nozzles 32 for accommodating the nozzles and preventing any crushing pressure thereagainst. The upper ends of the recesses 38 terminate in openings or slots 39 in the upper inclined edge portion of the protector plate, and these openings 25 39 are of increasing lengths from the intermediate portion of the protector plate toward the ends thereof to snugly receive therein the upper outlet ends 33 of the nozzles, and the outlet ends 33 are beveled in the plane of the outer face of 30 the protector plate so that lubricant ejected through the open ends 33 will be held against the side of the rail head and the upper edge portion of the protector plate and will not flow downwardly about the nozzles 32 and against the inner 35 side of the protector plate. It will be noted from Figure 1 particularly, that the protector plate is provided with relatively long blank portions 40 between the nozzle openings 39, and these blank portions 40 are of sufficient extent to receive and 40 guide the wheel flanges over the openings 39 so that the wheel flanges will have no tendency to engage against the upper open ends of the nozzles 32. The blank portions 40 of the protecting plate thus provide a substantially smooth and uninter- 45 rupted guiding surface for the wheel flanges.

It will be noted particularly from Figures 1 and 2 that the upper open ends 33 which provide the discharge mouths for the nozzles 32 are of various port areas corresponding to the respective sizes of 50 the nozzles 32 and increase successively from the point of entrance 29 of the lubricant toward the opposite ends of the distributing pipe. It will also be observed from Figure 4 that these discharge ends or mouths 33 of the nozzles lie in 55 close contact with the side of the rail head 17 so that the lubricant will be fed directly to the side of the rail head in the path of the wheel flange. The mouths or outlets 33 of the nozzles are flat and elongated in the direction of the 60 rail so as to provide a larger area over which the grease or lubricant is deposited on the rail head and wheel flange. The bracket 18 is vertically adjustable against the side of the rail and the distributing pipe 28 with its nozzles 32 is 65 adjustable therewith so as to deposit the lubricant at the proper elevation with respect to the rail head and wheel flange. The protector plate 34 is independently adjustable on the bracket 18 so as to fit the protector plate about the mouths 33 70 of the nozzles when the latter are adjusted not only as to height but also as to inclination to insure that the nozzles are fully protected from contact with the wheel flange or other objects brought against the side of the rail. 75

When the device is applied as illustrated, grease or other lubricant is fed under pressure through the inlet 29 to the distributing pipe head 28. The lubricant under pressure passes toward the opposite ends of the header and is ejected upwardly through the nozzles 32, the nozzles of smaller cross sectional area receiving the lubricant adjacent the inlet pipe and retarding the too free ejection of the lubricant so that the pressure throughout the body of lubricant will be equalized in the outer nozzles 32 which are of increasing cross sectional area. In this manner and by this construction the lubricant will be ejected uniformly from all of the nozzles throughout the length of the device and the distribution of the lubricant will therefore be uniform and may be more readily controlled.

It is obvious that various changes and modifications may be made in the details of construction and design of the above specifically described embodiment of this invention without departing from the spirit thereof, such changes and modifications being restricted only by the scope of the following claims.

25 What is claimed is:—

1. A rail flange lubricator comprising a bracket, means for adjustably securing the bracket against one side of the web of a rail, a distributing pipe mounted to turn on said bracket and having a plurality of outlet nozzles extending upwardly for engagement against the side of the head of the rail, and a protector plate adjustably mounted on the bracket and engaging across the outer sides of said nozzles for protecting the same.

35 2. A rail flange lubricator comprising a bracket, means for adjustably clamping the bracket against one side of the web of a rail, supporting means carried by the bracket for adjustment against the base of the rail for holding the bracket at the desired height against said rail web, a distributing pipe clamped upon said bracket and having a plurality of nozzles extending upwardly from the pipe for engagement against the side of the rail head, said pipe adapted to be turned 45 on the bracket for bringing the upper outlet ends of said nozzles against the rail head, and a protector plate adjustably mounted on the bracket and engaging over the upper portions of said nozzles for protecting the same, said protector plate having nozzle receiving recesses in its inner side for receiving said nozzles and having notches in its upper edge for receiving the upper open ends of the nozzles therein.

55 3. A rail flange lubricator comprising a bracket plate having vertical slots in its opposite ends and provided with supporting lugs projecting from the opposite ends of the bracket plate, clamping bolts engaging through the slots of the bracket plate and for engagement through the web of a rail for supporting the bracket plate at a desired height against said web, set screws threaded through said lugs for engagement with the base of a rail for holding the bracket plate at an adjusted elevation, said bracket plate having a plurality of spaced apart blocks on its outer face and with threaded studs projecting from the blocks, a distributing pipe secured along the lower portion of said bracket for vertical adjustment therewith and having outlet nozzles extending 65 upwardly from the pipe between said blocks, said nozzles having beveled outlet ends adapted for engagement against the side of a rail head, and a protector plate having vertical slots therein engaging over said threaded studs and supported 70 on said blocks, said protector plate extending

over said nozzles to protect the same and having notches in its upper edge conforming to the configuration of the upper ends of the nozzles to protect the same and prevent overflow of lubricant from the nozzles downwardly over the same. 5

4. A rail flange lubricator comprising a bracket plate, means for adjustably securing the bracket plate against one side of a rail, said plate having on its outer side spaced blocks with threaded studs extending from the blocks and inclined 10 outer faces at the bases of the studs, a pair of clamps mounted on said bracket plate in line with said blocks, a distributing pipe mounted in said clamps and adapted to be turned therein for adjustment and having upwardly extending noz- 15 zles adapted to be swung into contact with the side of the rail head, and a protector plate mounted on said blocks and having openings therethrough for the reception of studs, said studs having clamping nuts on their outer ends for binding the 20 protector plate to the block and against the side of the rail head.

5. A rail flange lubricator comprising a bracket, means for adjustably securing the bracket against one side of a rail beneath the head thereof, a 25 distributor mounted on the bracket and having a header with an inlet intermediate its ends for the reception of the lubricant under pressure, said header having a plurality of upwardly ex- 30 tending nozzles spaced lengthwise of the header and having longitudinally flattened mouths at their upper end for delivering lubricant under pressure against the side of the rail head, and a protector plate mounted on said bracket across the outer sides of said nozzles for protecting the 35 same and having a beveled upper edge with notches therein conforming to the configuration of the mouths of the nozzles for protecting the same and preventing overflow of lubricant below the nozzles. 40

6. A rail flange lubricator comprising a bracket plate having vertical slots in its ends and supporting lugs projecting beyond the lower corners of the plate, clamping bolts engaging through said slots and for engagement through the web 45 of a rail for binding the bracket thereagainst, set screws threaded downwardly through said lugs for engagement with the base of the rail to support the bracket plate, said bracket plate having vertical ribs near its opposite ends and having 50 spaced apart blocks in longitudinal alignment with the ribs, said blocks and ribs having outstanding threaded studs thereon and the blocks provided with upwardly and inwardly inclined supporting faces, a distributing pipe mounted on 55 the bracket and comprising a header disposed beneath the blocks and across the lower ends of said ribs, clamps engaging said header and seated on said ribs and provided with lugs on their upper ends engaging over the threaded studs of the ribs 60 and against the latter, said lugs having outer inclined faces disposed in the plane of the inclined faces of the blocks, a plurality of spaced apart nozzles carried by said header and extending upwardly between the blocks, and a protector plate 65 seated across the blocks and the lugs and having openings therethrough for the reception of the threaded stud, said protector plate having recesses in its inner side to receive said nozzles and protect the same and having an upper beveled 70 edge with notches therein registering with the upper ends of the nozzles to protect the same and direct lubricant from the nozzles to the rail head and wheel flange.

7. A rail flange lubricator comprising a bracket, 75

- means for adjustably securing the bracket to the side of a rail, a distributor mounted on the bracket and comprising a header having an intermediate inlet and provided with spaced apart nozzles extending upwardly from the header for engagement against the side of the rail head, said nozzles increasing in cross sectional area consecutively from the opposite sides of said inlet for equalizing the pressure of grease throughout the length of the distributor pipe, and a protector plate mounted on said bracket across the outer sides of said nozzles and having notches in its upper edge registering with the outlet ends of the nozzles for directing lubricant therefrom to the side of the rail head and in the path of wheel flanges.
8. A rail flange lubricator comprising a bracket, means for adjustably supporting the bracket at one side of a rail, said bracket having spaced blocks on its outer face with clamping means carried by the blocks, a distributing pipe mounted upon the bracket for adjustment therewith and having upwardly extending nozzles engaging between the blocks and adapted to engage against the side of the head of the rail, and a protector plate mounted on said clamping means of the blocks and extending over said nozzles with the upper edge of the plate for engagement against the side of the rail, said plate having notches in its upper edge for the reception of the upper ends of the nozzles, the portions of the plate lying between the nozzles adapted to engage the side of the rail and hold the plate from crushing said nozzles and providing a smooth and uninterrupted guide for the wheel flanges over the ends of the nozzles.
9. A rail flange lubricator comprising a bracket, means for adjustably securing the bracket to the side of a rail, a distributing pipe mounted on the bracket and including a header pipe, removable plugs mounted in the opposite ends of said header pipe for facilitating cleansing of the pipe, an inlet connection intermediate the ends of the header pipe for releasing lubricant under pressure, a plurality of nozzles extending upwardly from the pipe and spaced lengthwise thereof, said nozzles increasing in diameter consecutively from said inlet to the opposite ends of the header pipe and having flattened upper end mouths increasing in length consecutively from the inlet to the ends of the header pipe, said mouths of the distributor adapted to engage against the side of the rail head, and a protector plate mounted on the bracket and engaging over the outer sides of said nozzles to protect the same.
10. A rail flange lubricator comprising a bracket, means for adjustably mounting the bracket at the side of a rail, a distributing pipe adjustably mounted on the bracket and having upstanding nozzles for engagement against the side of the rail and provided with downwardly and outwardly beveled upper ends providing outlet mouths for the nozzles to distribute lubricant against the side of the rail head, and a protector plate carried by the bracket across the outer sides of said nozzles, said protector plate having vertical recesses in its upper portion adapted to receive said nozzles therein to protect the nozzles against crushing, said protector plate engaging the side of the rail head and provided with notches in its upper edge registering with said recesses and with the mouths of said nozzles.
11. A rail flange lubricator comprising a bracket, means for securing the bracket against the side of a rail, a distributing pipe mounted on the bracket and having a plurality of spaced apart nozzles extending upwardly for engagement at their upper ends against the side of the rail head, said nozzles increasing in port area consecutively from the intermediate portion of the distributor pipe to the ends thereof, and a protector plate mounted on the bracket over the outer sides of said nozzles and engaged at its upper edge against the rail head to protect the nozzles against crushing, said protector plate having notches in its upper edge conforming to the exterior size and configuration of the nozzle ends to register therewith and protect the same.
12. A rail flange lubricator comprising a bracket, means for securing the bracket against the side of a rail beneath the head thereof, a distributor mounted on the bracket and having upwardly extending nozzles with flat outlet mouths adapted for engagement against the side of the rail, said distributor pipe having an inlet for connection with a source of lubricant under pressure, said nozzles increasing in port area consecutively from said inlet, and a protector plate mounted on the bracket over the outer sides of the nozzles to protect the same and having notches in its upper edge conforming to the upper open ends of the nozzles for guiding wheel flanges thereover and preventing downflow of lubricant from the nozzles.
13. A rail flange lubricator comprising a bracket plate, means for securing the bracket plate against the side of a rail, said bracket plate having a longitudinal row of spaced apart blocks at its upper portion and having outstanding ribs beyond the blocks, said plate also having threaded studs extending outwardly from the ribs and the blocks, a pair of clamps mounted on said ribs over the threaded studs and having recessed lower ends, the outer faces of said lugs and said blocks being inclined upwardly and inwardly in a common plane, a distributing pipe mounted in the recesses of said clamps against said bracket plate and having nozzles extending upwardly between said blocks for engagement against the side of the rail head, and a protector plate having vertical slots therein engaging over said threaded studs and resting against said inclined faces of the blocks and lugs, clamping nuts mounted on the outer ends of said studs for binding engagement against the protector plate for securing the same in adjusted position, said nozzles having flattened mouths at their upper ends and said protecting plate having notches conforming to said mouths for engaging thereabout, the upper edge of said protector plate bearing against the side of the rail head to protect the nozzles and mouths against collapsing under pressure of wheel flanges.
14. A rail lubricator comprising a bracket adapted to be attached to the web of a rail, conduit means on said bracket extending longitudinally thereof, a plurality of parallel nozzles extending upwardly from said conduit means and terminating at the upper end thereof adjacent the head of the rail, and means on said bracket covering the outer sides of said nozzles for protecting the same, the cross sectional area of the mouth portion of the nozzles being greater for the nozzles remote from the center of the bracket and smaller for the nozzles adjacent the center.
15. A rail lubricator comprising a bracket adapted to be secured to the web of a rail and

having conduit means associated therewith, a plurality of pipes extending from said conduit means, the upper ends whereof terminate adjacent the head of the rail, a protector plate attached to said bracket, and said pipes being located between said bracket and protector plate, said protector plate being formed with recesses receiving said pipes.

16. A rail lubricator comprising a bracket plate having vertical slots in its opposite ends, clamping bolts engaging through the slots of the bracket plate for engagement through the web of the rail for supporting the bracket at a desired height against the web, set screws threaded to the bracket for engagement to the base of the rail for holding the bracket plate at an adjusted elevation, a longitudinal conduit means associated with said bracket and having a plurality of outlet pipes communicating therewith and extending upwardly, and a protector plate secured to said bracket and extending over said nozzles to protect the same, and having recesses on the inner surfaces thereof receiving said nozzles.

17. A rail lubricator comprising a bracket plate having vertical slots in its opposite ends, clamping bolts engaging through the slots of the bracket plate for engagement through the web of the rail for supporting the bracket at a desired height against the web, set screws threaded to the bracket for engagement to the base of the rail for holding the bracket plate at an adjusted elevation, a longitudinal conduit means associated with said bracket and having a plurality of outlet pipes communicating therewith and extending upwardly, and a protector plate secured to said bracket and extending over said nozzles to protect the same, and having recesses in the inner surfaces thereof receiving said nozzles, said protector plate having a beveled upper edge and said recesses extending to said upper edge.

18. A rail lubricator comprising a bracket and having a longitudinal conduit associated therewith, removable plugs for closing the ends of said conduit means, said conduit means having an intermediate inlet and provided with spaced apart nozzles extending upwardly for engagement with the side of the rail head, and a protector plate secured to said bracket and covering said nozzles, said nozzles increasing in cross-sectional area consecutively from the opposite sides of said inlet for equalizing the pressure of grease pumped to said conduit means.

19. A rail lubricator comprising a bracket and having a longitudinal conduit associated therewith, removable plugs for closing the ends of said conduit means, said conduit means having an intermediate inlet and provided with spaced apart nozzles extending upwardly for engagement with the side of the rail head, and a protector plate secured to said bracket and covering said nozzles, said nozzles increasing in cross-sectional area consecutively from the opposite sides of said inlet for equalizing the pressure of grease pumped to said conduit means, said protector plate having at its upper edge notches registering with the outlet ends of the nozzles.

20. A rail lubricator comprising a bracket and

having a longitudinal conduit associated therewith, removable plugs for closing the ends of said conduit means, said conduit means having an intermediate inlet and provided with spaced apart nozzles extending upwardly for engagement with the side of the rail head, and a protector plate secured to said bracket and covering said nozzles, said nozzles increasing in cross-sectional area consecutively from the opposite sides of said inlet for equalizing the pressure of grease pumped to said conduit means, said protector plate having at its upper edge notches registering with the outlet ends of the nozzles, the portions of the protector plate lying between the nozzles being adapted to engage the side of the rail head and hold the plate from crushing the nozzles and providing smooth and uninterrupted guide flanges of rail wheels passing over the rail.

21. A rail lubricator comprising a member adapted to be attached to the web of a rail, a plurality of spaced, parallel pipes mounted on said member, means for pumping grease to said pipes, the upper ends of said pipes terminating adjacent the rail head and being flattened, and a plurality of said pipes having mouths of different transverse cross-sectional areas.

22. A rail lubricator comprising a member adapted to be attached to the web of a rail, a plurality of spaced, parallel pipes mounted on said member, means for pumping grease to said pipes, the upper ends of said pipes terminating adjacent the rail head, and being flattened, a plurality of pipes having mouths of different transverse cross-sectional areas, and means covering said pipes for protecting the same against crushing by the flange of a wheel passing over said rail.

23. A rail lubricator comprising a bracket adapted to be attached to the web of a rail, conduit means associated with said bracket, a plurality of upstanding nozzles in communication with said conduit, said nozzles being provided with downwardly and outwardly beveled upper ends providing mouths for the nozzles to distribute lubricant against the side of the rail head, and a protector plate carried by the bracket across the outer sides of the nozzles, said protector plate having vertical recesses adapted to receive said nozzles therein to protect the nozzles against crushing, said protector plate engaging the side of the rail head and being provided with notches in its upper edge registering with said recesses and with the mouths of said nozzles.

24. A rail lubricator comprising a member adapted to be attached to the web of a rail between the head and the flange thereof, conduit means associated with said member and extending longitudinally thereof and having an inlet opening, a plurality of pipes extending from said conduit means and being open at the upper ends thereof, and said upper ends terminating adjacent the side of the rail head, a protector plate secured to said member and covering said pipes, the adjacent surfaces of said member and plate being formed with registering recesses receiving said pipes.

CHARLES STERN.
